METHOD OF LABELING

George W. von Hofe, Bound Brook, and Charles A. Claus, Short Hills, N. J., assignors to New Jersey Machine Corporation, Hoboken, N. J., a corporation of New Jersey

Application January 4, 1938, Serial No. 183,314

1 Claim. (Cl. 216—62)

The invention relates to methods of labeling and more particularly to labeling methods whereby pregummed labels, that is labels with dry coatings of adhesive, are used in the labeling process. The invention has for its object to provide a novel method whereby the application of the pregummed labels is effected in a uniform and efficient manner. The invention contemplates further the provision of a method whereby the dry adhesive coatings are treated in a manner to insure instantaneous and efficient adhesion of the labels to the articles for which they are intended. Other more specific objects will appear from the description hereinafter and the features of novelty will be pointed out in the claim.

In the accompanying drawing which shows an example of an apparatus for carrying out the novel method, Fig. 1 is a diagrammatic view of said apparatus, and Fig. 2 is a detail enlarged section on the line 2—2 of Fig. 1.

The novel method of labeling comprises removing pre-gummed labels, that is labels provided with dry coatings of adhesive, in individual succession from the bottom or equivalent end of a supply stack with the adhesive surfaces of said labels exposed, carrying each removed label into the presence of a spraying liquid to moisten the adhesive coated surface thereof, permitting said moistened adhesive coating to season for a predetermined time period, transferring each label subsequently to the seasoning of the adhesive coating, into applying relation to an article, and applying said label thereto. Under some conditions, the step of definitely permitting the moistened adhesive coating to season may be omitted, although otherwise the method may be the same as described above.

As shown diagrammatically in Fig. 1 of the drawing, a supply of labels 5 is arranged in the form of a preferably upright stack with the adhesive coated surfaces of the labels facing upwardly in said stack; the arrangement is such that the stack is accessible at its lower or equivalent end to permit successive terminal labels to be individually removed therefrom. The stack 5 accordingly is preferably contained in a suitable stationary hopper 6 open at its lower or equivalent end and including any conventional means, such as resilient detents 7, for maintaining the stack 5 in the hopper 6 without interference with the removal of successive terminal labels from the bottom or equivalent end thereof.

In the diagrammatically illustrated example, 55 the mechanism which co-operates with the stack

of labels 5 in carrying out the method, comprises a carrier 8 rotatable on a suitable stationary axis 9 preferably in intermittent steps in any conventional and well-known way. The carrier 8 is provided with a plurality of members extending 5 radially outward therefrom and partaking of the intermittent movement of said carrier 8; the illustrated diagrammatic example shows four members each consisting of a main section 10 and an auxiliary section 11 telescopically combined with the main section 10 and longitudinally movable relatively thereto by any suitable means in operative synchronism with the co-operating parts of the mechanism. To diagrammatically illustrate the aforesaid longitudinal 15 movements, each section 11 is loosely connected at 12 with an arm 13 pivoted at 14 upon a bracket 15 projecting from the associated section 10. Each arm 13 in turn is pivotally connected at 16 with a rod 17 slidably mounted in a bearing 18 20 and carrying a roller 19 in engagement with a cam 20 fixed upon the shaft 9; a spring 21 is mounted on each rod 17 and tends to move the co-operating section 11 outwardly relatively to its associated section 10.

Each auxiliary section 11 is provided at its outer end with a pick-up device for removing terminal labels from the bottom or equivalent end of the stack 5 in individual succession, each device being diagrammatically illustrated in the form of a suction head 22 suitably connected with a source of suction in any well-known way; provision is made in any customary manner for controlling the suction effective in the heads 22 in predetermined synchronism with the operative steps performed by said mechanism. For instance, the axis 9 may consist of a hollow cylinder connected by means of a tube 23 with a source of suction arranged to develop a constant suction in the interior 24 of the axis 9 during 40 when the apparatus is in operation. The axis cylinder 9 is provided with a circumferential slot 25 arranged to register with ports 26 in the carrier 8; in such case the sections 10 and 11 may include internal passages 27 which connect the 45 ports 26 with the heads 22 or their equivalent.

In addition to the parts so far described, the mechanism diagrammatically shown in the drawing includes a spraying device 28 connected in any convenient way with a source of water or 50 other liquid preferably under pressure, it being understood that means is provided for controlling the spraying device 28 in accordance with the predetermined operative cycle of the mechanism. The arrangement further includes a mov-

able support for the articles to be labeled, which support may comprise a conveyor 29 operated intermittently to bring the articles to be labeled, such as bottles 30, to the labeling station as will 5 appear more fully hereinafter. While the bottle 30 shown in the diagrammatic illustration occupies an upright labeling position on the conveyor 29, it will be understood that said bottle 30 or other article, may be otherwise positioned for 10 labeling on said conveyor 29 and also that the latter may be replaced by any other well-known means for accomplishing the same or an equivalent purpose.

For purposes of description, it may be assumed 15 that the stack of labels 5 is located at a pick-up station A, that the spraying device 28 is located at a spraying station B in spaced relation to the pick-up station A, and to a seasoning station C which in turn is in spaced relation to the labeling 20 station D; in some installations, the seasoning station C may be omitted. It will be understood that the stations A, B, C, and D are located at spaced intervals in operative relation to the path intermittently traversed by the suction heads 22 25 or equivalent pick-up devices; in the diagrammatic illustration, the several stations are accordingly located at 90° intervals in operative relation to the circular path over which the suction heads 22 move intermittently during 30 any given operative period of the mechanism. The above is obviously true also if the station C is omitted, although the spacing arrangement in such case may be somewhat different, the latter always being dependent upon the type of 35 mechanism and the operative cycle developed thereby.

In the operation of carrying out the novel method previously described herein, the carrier 8 is rotated one step in the direction of the arrow 40 to bring one of the suction heads 12 or its equivalent to the pick-up station A beneath and temporarily at rest in registry with the lower end of the stack 5; at this station A the co-operating roller 19 will drop into a recess of the cam 20 45 under the influence of the associated spring 21 and thereby will rock the arm 13 in a direction to shift the section 11 outwardly of the section 10 and cause said suction head 22 to be operatively moved into contact with the lowermost terminal label of said stack 5. At this stage the port 26 and internal passage 27 of the given sections 10 and 11 will register with the slot 25 so 50 that suction is made effective in the suction head 22. As the intermittent rotation of the carrier 8 is resumed, the roller 19 will ride out of the cam recess whereby the rod 17, arm 13 and section 11 are operated to shift the suction head in a 55 downward direction in the diagrammatic illustration to thereby withdraw and remove the terminal label from the lower or equivalent end of the stack 5. The second step in the rotation of the carrier 8 is continued until the suction head 22 and the label held thereon is moved to the spraying station B into registry with the spraying 60 device 28, it being understood that at this stage the adhesive coated surface of said label faces the aforesaid spraying device 28. During the rest period which follows this latter operation, a spray of water or other suitable liquid is 65 expelled from the spraying device 28 on to and over the adhesive coated surface of the label which is located at the spraying station B at the time. This spray of water or other liquid serves to moisten the adhesive coated surface of the label 70 and thereby softens the same and renders the 75

adhesive tacky. The carrier 8 is then again actuated, subsequently to the moistening of the adhesive coating of the label, to bring the suction head 22 and said label to the seasoning station C at which said label is permitted to remain for 5 a predetermined time period during which the moistened and softened coating of adhesive is permitted to season. At the end of the seasoning period the operation of the carrier 8 is renewed to bring the suction head 22 and the label carried thereby to the labeling station D. In the meantime, the conveyor 29 or its equivalent has been actuated to bring an article, such as the bottle 30, into labeling position at said station D in engagement with a backing device 31 located 15 thereat. As the station D is reached, the roller 19 associated with a given suction head 22 will pass into a second recess of the cam 20 whereby the co-operating rod 17 and arm 13 are actuated by the spring 21 which controls the same to 20 operatively shift the suction head 22 toward the bottle 15 or other article, at the labeling station D to bring the adhesive coated surface of the particular label into initial adhesive engagement with said bottle 30 or other article. At the appropriate moment, subsequent to the initial adhesive engagement of said label with the bottle 30 or its equivalent, the port 26 and the particular internal passage 27 related to the given suction head 22 will pass beyond and out 30 of registry with the circumferential slot 25 whereby suction in the particular suction head 22 is discontinued; it will be understood that the circumferential length of the slot 25 is such that suction will be maintained in a given 35 head 22 during the successive steps in which it travels from the station A to the station D. As the intermittent rotation of the carrier 8 is resumed, the given roller 19 will pass out of the second recess of the cam 20 to the periphery 40 thereof, and the associated rod 17 and arm 13 will accordingly be actuated to shift said suction head 22 in a direction away from the bottle 30 or its equivalent, the previously deposited label remaining in adhesive engagement with said bottle 30 or other article, as these last named operations take place. The application of the label 45 subsequent to its initial engagement with the bottle 30 or other article is then completed in any conventional manner and at the same time 50 the given suction head 22 is again shifted to the pick-up station A, whereupon the aforesaid steps are repeated.

The steps in the novel method set forth above are effected in a corresponding manner by the 55 suction heads carried by the other members which extend radially outward from the carrier 8, so that the various steps of the method are being carried out successively and in sequence at the different stations throughout a given 60 operative period of the mechanism, as will be clear.

Under certain conditions, the definite rest period at the seasoning station C may be omitted or, in other words, the seasoning of the adhesive coating may be omitted, in which case the label 65 subsequent to the moistening and softening of the adhesive coating at the station B may be shifted directly to the applying station D for application to the article to be labeled.

The novel method makes it possible to utilize 70 pre-gummed labels or labels provided with dry coatings of adhesive where such is desired, and to apply said labels to the articles for which they are designed, in an efficient and continuous manner. As is evidenced by the diagrammatic illus- 75

tration, the method may be mechanically performed by mechanism of maximum simplicity, requiring no particular skill in its supervision.

Various changes in the specific forms shown 5 and described may be made within the scope of the claim without departing from the spirit of the invention.

We claim:

A method of labeling which consists in re- 10 moving labels each having a coating of dry ad-

hesive on one surface in individual succession from a supply stack with the dry adhesive coated surface of each successive label exposed, spraying the adhesive coated surface of individual labels with a liquid to soften said adhesive, permitting said softened adhesive to season for a predetermined time period, and subsequently to the seasoning period applying the label to an article. 5
